By R. S. & A. Lacey Atty's

UNITED STATES PATENT OFFICE.

BENJAMIN KEPNER, OF PHILADELPHIA, PENNSYLVANIA.

AUTOMATIC SCREEN CHUTE, GATE, COAL-BIN, &c.

SPECIFICATION forming part of Letters Patent No. 325,343, dated September 1, 1885.

Application filed June 30, 1885. (No model.)

To all whom it may concern:

Be it known that I, BENJAMIN KEPNER, a citizen of the United States, residing at Philadelphia, in the county of Philadelphia and State of Pennsylvania, have invented certain new and useful improvements in automatic screen chutes and gates, and double-incline-plane-bottomed coal bins or pockets, and dust-box and screen attachments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in coal-chutes; and it consists in the combination and arrangement of the several parts herein-after described, and pointed out in the claims.

In the drawings, Figure 1 is a plan view of a coal-bin constructed according to my invention. Fig. 2 is an end elevation of the same. Fig. 3 is a longitudinal section of the same. Fig. 4 is a detail view.

In the accompanying drawings, A is the bin, pocket, or receptacle, of rectangular or any other desired shape, with inclined planes B B, forming the bottom and pitching from the center or apex C downward. I have shown in the drawings only two inclines B; but it will be understood that the bottom of the bin or pocket could be made in the shape of a pyramid having four inclines, in which case I could use four chutes and screens of pattern herein-after described.

At the lower end of each inclined plane a discharge-opening, D, is formed through the side of the receptacle, and through this opening the coal runs onto the chute.

A gate, E, is arranged to close the discharge-opening. The gate is held down by weights or springs. I prefer to employ a spring, E', as shown, though any counterbalancing force known in mechanics could be employed. The spring is only one of these forces, and I do not limit myself to its use. To the framing I hinge the screen-chute F, which is arranged to receive the coal as the latter emerges from the

receptacle. The chute is provided with a screen-bottom, F', and it is connected with the gate E by a cord or chain, E'', which passes over a pulley, E', journaled in the framing just above the discharge-opening. Instead of 55 a single cord and chain and a single pulley, two cords or chains and two pulleys could be used. I prefer one of each, and arranged as shown. The spring E' is of such strength that it will hold the gate down and the chute in a 60 horizontal position. By pulling the outer end of the chute down the gate is raised so that the coal can flow through the discharge-opening.

Just below the screen-chute I arrange a return-chute, G, which has the upper side of its 65 outer end made on an incline to permit the pulling down of the said screen-chute. The inner end is provided with a screen, G'', arranged over the dust-box G'. The dust-box 70 may have drawers in it, or it may be a plain box, from which the dust may be shoveled.

A track, H, for the coal-cars can be arranged on the top of the receptacle, as shown.

I prefer to have the screen chute and gate connected together and simultaneously operated, as hereinbefore described, but a rope or lever could be secured and used to raise the gate, and a separate weight could be attached to the cords which draw up the screen-chute. The screen-chute when raised to the horizontal 80 position would prevent the coal from running out in case the gate was accidentally raised. A small portion of the coal would run out onto the inner edge of the screen-chute, but not sufficient to depress the latter. 85

Having thus described my invention, what I claim, and desire to secure by Letters Patent, is—

1. The combination of a coal-hopper having an inclined bottom and a discharge-opening, a vertically-sliding gate to close the discharge-opening, a hinged spring-chute arranged on the outer side of the coal-receptacle at the lower side of the discharge-opening, a flat spring bearing on the upper edge of the gate, and a 95 cord attached to the chute passing over a pulley and connected to the gate, as and for the purposes set forth.

2. The combination, with the coal-hopper A, having discharge-opening D, of the screen F, 100

hinged to said receptacle below the discharge-opening, and the return-chute G, extending beyond the hopper, its inner end, G², projected beneath the hopper and forming the dust-box 5 G', substantially as shown and described.

3. The combination of the hopper A, having double-inclined bottom B B, and discharge-openings D, track H, located immediately over the apex of the bottom, vertically-sliding doors 10 E, flat spring E', hinged spring-chutes F, cord E', connecting the latter with the doors, re-

turn-chute G, and screen-extension G², forming the dust-receptacles G', the parts constructed, arranged, and operating substantially as shown and described.

In testimony whereof I affix my signature in presence of two witnesses.

BENJAMIN KEPNER.
